UNITED STATES PATENT OFFICE.

GEORGE H. KNOSTMAN, OF MINSTER, OHIO.

EGG-CARRIER.

1,324,828.

Specification of Letters Patent. Patented Dec. 16, 1919.

Application filed September 19, 1917. Serial No. 192,148.

To all whom it may concern:

Be it known that I, GEORGE HENRY KNOSTMAN, a citizen of the United States, and a resident of Minster, in the county of Auglaize and State of Ohio, have invented certain new and useful Improvements in Egg-Carriers, of which the following is a specification.

This invention relates to protective containers, and more particularly to a carrying and transporting container for eggs, glass articles, and other similar fragile articles which often become broken in transit.

The principal object of the invention is to provide an improved space container for transporting eggs from place to place by parcel post, express and freight shipments with assurance that the eggs will arrive at their destination intact and unbroken.

As a further object of the invention, the device includes yieldable packing material in which the eggs are nested and uniformly spaced apart so that contact with each other or with adjacent hard substances will be prevented.

Other objects of the invention will readily appear from a consideration of the following detailed description of the invention and of the preferred embodiment illustrated in the accompanying drawing, wherein:

Figure 1 is a perspective view of the receptacle showing the ends thereof partly opened.

Fig. 2 is a perspective view of the inner container.

Fig. 3 is a transverse section through the same.

Referring to the drawing, wherein is illustrated the preferred form of this invention and in which like characters of reference indicate the corresponding parts throughout the several views, a retaining frame 1 is constructed of rectangular formation, as shown in detail in Fig. 2 and this frame is preferably constructed from light wood having the two sides 2 and the end walls 3, the ends of which are fastened together to form the frame. This frame is preferably constructed of wood although it will be obvious that heavy cardboard, thin metal or any other suitable material may be employed in constructing the frame.

A quantity of excelsior is placed within the frame and is preferably saturated with a suitable adhesive or glue which, in the present instance, consists of 50% flexible cabinet

glue, 25% starch and 25% gleichs liquid glue. This substance is worked into the excelsior so that the stuffing or protective mass may be shaped as desired, and a plurality of compartments are formed for the reception of the eggs. While excelsior, consisting of shreds of wood or wood pulp, is stipulated, I desire to be understood that any fibrous material may be employed in stuffing the frame 1 to provide the yieldable protective mass for receiving the eggs. It will be obvious that the compartments may be formed of different shapes to receive glass articles such as electric-light bulbs, fragile glass ornaments, or the like, and when the adhesive is dry, the stuffing will possess the flexibility and resiliency that will prevent injury to the contents when the container receives a severe jar as often occurs when shipping containers of this character are in transit.

An exterior casing 4 is provided for the frame and consists of a rectangular receptacle adapted to snugly receive the frame 1 and has its ends open to permit the frame to be thrust into or out of the casing from either end thereof. The end walls 5 of the casing are foldable to permit them to be swung up into closed position where they may be fastened by a binding cord or strap 85 in any preferred manner and it will be also apparent that a number of these cases containing the filled frames may be packed in a shipping box or case and contact of the ends of the casings with each other will maintain them in closed position. This exterior casing or cover may be constructed from wood, straw-board or corrugated cardboard.

From the foregoing, it will be observed that a very simple and durable protective shipping carrier has been provided, the details of which embody the preferred form. I desire to be understood, however, that slight changes may be made in the details of construction without departing from the spirit of the invention or the scope of the claims hereunto appended.

What is claimed is:

1. A carrier comprising a retaining frame, a quantity of excelsior placed within the frame and provided with a plurality of spaced compartments formed by open portions in the excelsior, the latter being saturated with a quantity of adhesive.

2. A carrier comprising a mass of yieldable fibrous material, an adhesive co-mingled with the material to slightly stiffen the same

for giving a resiliency to the mass, and means embracing the mass to retain it in a predetermined form.

3. A carrier comprising a mass of yieldable fibrous material, the said mass being provided with a plurality of spaced compartments formed by open spaces in the said mass, a frame embracing the said mass, and a casing for receiving the said frame and the

10 said mass.

4. A safety carrier comprising a yieldable mass of fibrous material having a quantity of adhesive co-mingled therewith, the said material being provided with open

15 spaces to form a plurality of compartments, a frame embracing the sides of the said mass,

and a casing completely enveloping the said frame and the said mass.

5. A carrier comprising a mass of yieldable fibrous material saturated with adhesive 20 to form a resilient mass, said mass being provided with a plurality of spaced compartments opening into one side of the mass, and a confining frame embracing the edges of the said mass.

6. A carrier comprising a mass of yieldable fibrous material saturated with adhesive to form a resilient mass, said mass being provided with a plurality of spaced compartments opening into one side of the mass. 30

GEORGE H. KNOSTMAN.
